UNITED STATES PATENT OFFICE.

HENRY M. REICHENBACH, OF ROCHESTER, NEW YORK.

CARBURETER.

1,201,871.

Specification of Letters Patent. Patented Oct. 17, 1916.

Application filed April 9, 1913. Serial No. 760,008.

To all whom it may concern:

Be it known that I, HENRY M. REICHENBACH, a citizen of the United States, residing at Rochester, in the county of Monroe and State of New York, have invented certain new and useful Improvements in Carbureters; and I do hereby declare the following to be a full, clear, and exact description of the invention, such as will enable others skilled in the art to which it appertains to make and use the same.

My invention relates to improvements in carbureters and it consists in the constructions, combinations and arrangements herein described and claimed.

An object of my invention is to provide an improved carbureter adapted to operate efficiently with fuels having a high boiling point.

A further object of my invention is to provide an improved carbureter adapted to supply and maintain a fuel in a finely comminuted condition.

A further object of my invention is to provide improved carbureters for internal combustion engines, which will operate effectually to prevent deposition or accumulation of the fuel therein under all varying service conditions, thereby insuring a uniform and efficient mixture at all times.

In the accompanying drawings, forming a part of this application and in which similar reference symbols indicate corresponding parts in the several views:—Figure 1 is a side elevation, partly in section, illustrating one embodiment of my invention; Fig. 2 is a plan of the construction shown in Fig. 1; Fig. 3 is a section through Fig. 1; Fig. 4 is a section through Fig. 2; and Fig. 5 is a section on the line 5—5 of Fig. 1.

Referring to the drawings:—1 indicates a rectangular inlet conduit connected to a usual manifold 2 provided with intakes 3 to the cylinders of an internal combustion engine; said conduit being provided with a throttle valve 4 adapted to be manually or automatically actuated in any usual manner.

An inverted siphon 5 has one end 6 freely open to the atmosphere, and its other end 10 extending within said conduit 1 to constitute a fuel chamber 7 provided with apertures 8. An air supply pipe 9 is secured to the conduit 1 and provided with a series of nipples 10 discharging through said fuel chamber 7 coaxially with the apertures 8; the admission of air to said pipe 9 being controlled

by a ported valve 11 rotatably mounted therein.

A fuel feed pipe 12 is provided for conducting fuel from the usual float tank to a head 13 provided with a cylindrical bushing 14, in which a hollow valve 15 is rotatably and slidably mounted; said valve being provided with a rectangular port 16 adapted to coöperate with a similar port 17 in said bushing. A spring 18 is confined between said head 13 and a collar 19 on said valve 15 for yieldingly maintaining the latter depressed in closed position, as shown in Fig. 1. The valve 15 is provided with a pin or lug 20 in engagement with a cam rail 21 which latter is carried by a bracket 22; said bracket being adjustably secured to the conduit 1 by screws 23 extending through arc-shaped slots 24 in said bracket 75 concentric with the valve 15.

A rectangular air inlet valve 25 is pivotally mounted within the conduit 1 between the throttle valve 4 and fuel chamber 7 in position to be actuated by the suction of the engine for directing the indrawn air across the apertures 8 of said chamber.

A link 26 is suitably connected, as by ball and socket joints 27 and 28 to cranks 29 and 30 on the feed valve 15 and inlet valve 85 spindle 31; said link being provided with adjusting means, such as a turn buckle 32. The other end of the eduction valve spindle 31 carries a crank 33, which is connected to a crank 34 on the valve 11 of the air pipe 9 by a link 35 provided with a turn buckle 36. This provides a simple and advantageous means by which the fuel feed valve 15 and air valve 11 are simultaneously actuated by the suction of the engine; the degree of such actuation being proportionate to the extent of opening of the inlet valve 25 at all times.

The manifold 2, which constitutes a portion of the inlet conduit for the engine, is provided with a converging end nozzle 37 connected by a pipe 38 with a point in the manifold 2 at the opposite side of the usual valve-controlled engine intakes 3; said pipe 38 constituting a by-pass and being provided with a jacket 39 for the circulation of a suitable heating medium, such as the exhaust engine gases, cooling water from the cylinder jacket, steam, etc.

By this improved construction, the velocity of the current of combustible mixture drawn through the inlet conduit by the engine suction will cause said gaseous mix-

ture to sweep by its kinetic energy through the end nozzle 37 into the by-pass 38 upon any tendency to retard or check said current by a reduction in the aggregate amount 5 of mixture drawn through the engine intakes 3 or by stoppage of the engine. This provides a highly advantageous action, by which all residual or surplus fuel will be carried into the by-pass 38, and all danger of 10 troublesome deposition and accumulation of fuel in the inlet conduit will be eliminated, thereby insuring an efficient mixture under all operative conditions.

A U-tube 40 has one leg extending from 15 the bottom of the by-pass for draining by gravity any fuel condensed within said by-pass. The other leg 41 of said U-tube opens within the discharge end of said by-pass and has an atomizing air tube 42 communicating therewith; said leg and tube 42 being connected with the air supply pipe 9 by a pipe 42^a. The upper end of the leg of the U-tube is shown closed by a screw 42^b, which provides means for convenient access 20 in cleaning. This provides a simple and efficient means by which any fuel condensed in the by-pass 38, which is not reevaporated by the heating jacket 39 thereof, will collect in the U-tube 40 and be sprayed from said 25 tube into the inlet conduit by the injector action of the air drawn through tube 42 and pipe 42^a by the engine suction. This insures an efficient admixture of the fuel and provides an advantageous supply of fuel in 30 starting the engine.

If desired, the supply pipe 9 can be readily connected to a source of compressed air 9^a for starting; this is especially advantageous when employing a heavy fuel.

40 As the result of extensive experiment, I have discovered that the fine particles of a fuel which has been reduced to a nebulized condition by a strong atomizing action tend to repel one another, and that such repelling force acts to maintain the particles separated in the nebulized state. In order to advantageously utilize this action, I preferably line or coat the interior of the inlet conduit with a material which is insoluble 45 and immiscible, with and also, in a sense repellent to the fuel, the particles of fuel and the coating specified having probably become charged with static electricity of a potential different from that of the nebulized fuel, I have found that such a coating of shellac acts to minimize the accumulation of fuel on the conduit walls probably because of the smooth surface and oil repellent nature of the shellac coating; such action 50 is advantageously obtained with cast iron manifolds by employing a lining of porcelain or glass, which further tends to reduce surface adhesion. The friction of the fuel particles upon the walls of the conduit, especially when, as is often the case, 55

the air current assumes a helical or gyroscopic movement, probably establishes a difference of potential between said particles and the coating. Other coatings of dielectric character, may be used if they will not be affected by the fuel. 70

This novel construction insures the maintenance of a uniform combustible mixture within the inlet conduit and delivers the fuel directly to the engine in a finely divided and intimately admixed condition; thereby insuring a maximum efficiency and economy of operation. 75

The inverted siphon pipe 5 is surrounded by a removable casing 43 having an inlet pipe 44 and outlet pipe 45 for the circulation of a suitable heating medium therein, thereby providing means for efficiently heating and vaporizing the fuel fed to said pipe 5. 80

I have illustrated and described preferred and satisfactory constructions, but changes may be made within the spirit and scope of my invention. 85

I claim:—

1. In a carbureter, the combination of an inlet conduit for an internal combustion engine, a throttle valve therein, means between the throttle valve and the engine intake and controlled by the engine suction for directing the fuel in atomized condition transversely across said conduit and substantially at right angles to the draft in said conduit and means actuated by the engine suction for controlling the supply of fuel to said atomizer. 90

2. In a carbureter, the combination of an inlet conduit for an internal combustion engine, a throttle valve therein, a suction actuated atomizer opening into said conduit between said throttle valve and engine for directing the fuel in atomized condition transversely across said conduit and substantially at right angles to the draft in said conduit and means actuated by the engine suction for controlling the supply of fuel to said atomizer. 95

3. In a carbureter, the combination of an inlet conduit for an internal combustion engine, a throttle valve therein, means actuated by the engine suction for supplying fuel to said conduit between said throttle valve and engine, means for controlling the feed of fuel and air to the said supply means, a suction actuated air supplying valve in said conduit between said throttle valve and fuel supply means, and connections between said suction actuated valve and feed supplying means, for actuating the latter. 100

4. In a carbureter, the combination of an inlet conduit for an internal combustion engine, a throttle valve therein, means actuated by the engine suction for supplying fuel and air to said conduit between said throttle valve and engine, means for con- 105

130

controlling the feed of fuel to the said supply means, a suction actuated valve in said conduit between said throttle valve and supply means, and adjustable connections between 5 said suction actuated valve and feed supply means for actuating the latter.

5. In a carbureter, the combination of an inlet conduit having a coating of material which may become statically charged by 10 friction of fuel particles, for an internal combustion engine, a throttle valve therein, means actuated by the engine suction for supplying fuel and air to said conduit between said throttle valve and engine, and a 15 suction actuated valve between said throttle valve and supply means for directing the entering air across the latter.

6. In a carbureter, the combination of an inlet conduit for an internal combustion engine rectangular in cross section, in part at 20 least, a throttle valve in said conduit, a suction actuated fuel supply means opening into the bottom of said conduit between said throttle valve and engine, a suction actuated 25 valve shaped to correspond with the cross section of the conduit suspended from the top of said conduit between said throttle valve and fuel supply means for directing the entering air across the latter and means 30 coupling the fuel supply means and the suction-actuated valve so that they act in unison.

7. In a carbureter, the combination of an inlet conduit rectangular in cross section, in 35 part at least, for an internal combustion engine, a valve corresponding in outline to the said conduit pivoted to the upper side thereof, a crank attached to said valve, a link attached to said crank, a fuel supply 40 device arranged in said conduit in advance of said valve, a valve controlling said supply, a crank on said valve, said crank being connected to said link, and a discharge from said valve into the bottom of said conduit, 45 whereby, when the valve is moved in response to engine suction, it controls the sup-

ply of fuel and may direct the entering current across the discharge openings in the bottom of the rectangular-shaped conduit.

8. In a fuel feeding system, the combination of an inlet conduit communicating with the intake of an internal combustion engine, and an open by-pass communication with said conduit on opposite sides of the engine intake. 50

9. In a fuel feeding system, the combination of an inlet conduit communicating with the intake of an internal combustion engine, an open by-pass communicating with said conduit on opposite sides of the engine intake, and means for heating said by-pass. 55

10. In a fuel feeding system, the combination of an inlet conduit communicating with the intake of an internal combustion engine, an open by-pass communicating with said conduit on opposite sides of the engine intake, and spraying means for delivering into said conduit fuel entrapped in said by-pass. 60

11. In a fuel feeding system, the combination of an inlet conduit communicating with the intake of an internal combustion engine and terminating in a converging nozzle beyond said intake, and a by-pass leading from said nozzle to said conduit on 75 the opposite side of the engine intake.

12. In a fuel feeding system, the combination of an inlet conduit communicating with the intake of an internal combustion engine and terminating in a converging 80 nozzle beyond said intake, a by-pass leading from said nozzle to said conduit on the opposite side of the engine intake, and means actuated by the engine suction whereby fuel entrapped in said by-pass may 85 be drawn into the conduit.

In testimony whereof, I affix my signature, in presence of two witnesses.
